UNITED STATES PATENT OFFICE.

HENRY KOCOUREK, OF CHICAGO, ILLINOIS, ASSIGNOR TO CHICAGO FLEXIBLE SHAFT COMPANY, OF CHICAGO, ILLINOIS, A CORPORATION OF ILLINOIS.

ELECTRIC FLATIRON.

1,350,867.

Specification of Letters Patent.

Patented Aug. 24, 1920.

Application filed August 21, 1919. Serial No. 318,997.

To all whom it may concern:

Be it known that I, HENRY KOCOUREK, a citizen of the United States, and a resident of the city of Chicago, in the county of Cook and the State of Illinois, have invented certain new and useful Improvements in Electric Flatirons, of which the following is a specification, reference being had to the accompanying drawings, forming a part thereof.

The object of this invention is to provide a fitting to be attached to the body of an electric iron to serve as a rest therefor when the iron is tilted up on end, out of use, and formed to act also as a guide and guard for the separable plug through which the electric current is conducted to the heating element of the iron. It consists of the structure hereinafter described and shown in the drawings as indicated by the claims.

In the drawings:

Figure 1 is a side elevation of an electric iron provided with a back rest fitting embodying this invention.

Fig. 2 is a rear elevation of the rest with the body of the iron indicated in dotted outline.

Fig. 3 is a detail section taken as indicated at line 3—3 on Fig. 1.

The electric iron shown in the drawings comprises the usual body A, which incloses an electric heating element not shown, and which is provided with a handle B and electrical connecting means for the heating element in the form of two contact pins C, C, which project from the upper surface of the body A near the "heel" end of the iron. The back rest fitting is a sheet metal plate, 1, whose extreme upper edge portion, 2, is bent to extend rearwardly so as to serve as a supporting foot when the iron is tilted up on end. The lower part, 3, of the plate is likewise bent to project rearwardly when the iron is in normal working position and to serve for supporting it in up-tilted position. The edge, 4, of this lower portion is bent back upon itself to make a smooth rounded terminal which will not catch or snag upon the goods in a backward ironing stroke.

To minimize the conduction of heat from the body A to the rest plate, 1, the latter is connected to the body only by narrow strips, 5, 5, off-set from the plane of its main portion and secured to the body, A, by screws

or rivets 6, 6. The rest member is thus in contact with the heated body only at these narrow strips, 5, 5, whose limited cross section renders the conduction of heat to the rest member so slow that it is easily taken care of by radiation from the relatively much larger area of the member, 1, and it consequently keeps comparatively cool.

The member, 1, is made to serve another function by forming its upper portion, 7, with laterally extending arms, 8, 8, curved forwardly and inwardly toward each other and around the connector pins, C, C, in spaced relation thereto, so as to guide a separable current plug, D, into operative relation to the connectors and embrace and steady the plug in such position.

With the purpose of further retarding conduction of heat to the foot portion, 3, the plate, 1, may be transversely slotted across the greater part of its width as shown at, 9, adjacent the foot portion, 3.

I claim:

1. In combination with an electric flat iron a rest attached at the heel of the iron comprising a plate of sheet metal having narrow, lateral, marginal portions severed and offset toward the body of the iron from the plane of the plate between limits within the area of the plate, leaving said marginal portions joined to the plate at said limits, and attached at said offset strips to the body of the iron, whereby the remainder of said rest plate is held out of contact with said body.

2. In the combination defined in claim 1, the body of the iron having electrical connecting means projecting from its upper surface near the heel portion, and the upper part of said plate having lateral arms bent forwardly and inwardly toward each other around said connecting means for guiding a connecting plug into operative relation thereto.

3. In the combination defined in claim 1, the extreme upper edge of said plate being bent to extend rearwardly to serve as a supporting foot when the iron is tilted up on end.

4. In the combination defined in claim 1, both the upper edge portion and the lower edge portion of the plate being bent to extend rearwardly to serve as supporting feet when the iron is tilted up on end.

5. In the construction defined in claim 1

- 2
- foregoing, the extreme upper edge portion of said plate being bent to extend rearwardly to serve as a supporting foot when the iron is stood upon end, and the portion 5 intervening between said extreme portion and the offset lateral marginal portions being folded forwardly and inwardly from the opposite sides toward each other to constitute a clasp and guide for a conducting 10 plug.
6. In combination with an electric flat iron, a rest member having off-set lugs by which it is attached to the body of the iron,
- said member being held otherwise out of contact with said body and said lugs being 15 of relatively small cross-section at their junctions with the rest member, said member having its own cross section materially reduced adjacent said junctions by an aperture extending partially across its width to 20 retard conduction of heat to and within the rest member.

In testimony whereof, I have hereunto set my hand at Chicago, Illinois, this 14 day of August, A. D. 1919.

HENRY KOCOUREK.
